RECOVERING NITROGEN BASES FROM
MINERAL OILS

Barney R. Strickland, Roselle, N. J., assignor to
Standard Oil Development Company, a corpora-
tion of Delaware

Application October 31, 1940, Serial No. 363,639

7 Claims. (Cl. 260—269)

The present invention relates to the refining of mineral oils. The invention is, however, more particularly concerned with the removal and recovery of naturally occurring nitrogen bases from mineral oils containing the same. In accordance with the present process these materials are recovered in an efficient and economical manner by a process utilizing bauxite.

It is well known in the art to treat petroleum oils with various solid treating agents, as for example bauxite, zeolite and the like in order to improve their color and color stability. It has also been proposed to use these substances for the recovery and segregation of naturally occurring acidic oxygen-containing compounds, as for example petroleum naphthenic acids and petroleum oil phenols.

I have now discovered a process by which valuable naturally occurring nitrogen bases may be recovered from feed oils containing the same utilizing bauxite. In accordance with my invention, feed oils containing recoverable nitrogen bases are contacted preferably with activated bauxite under conditions to substantially fully remove these constituents from the feed oils. The spent bauxite containing the adsorbed nitrogen bases is then handled in a manner to remove and segregate these constituents in a relatively pure state and to fully regenerate the bauxite which is preferably recycled and contacted with fresh feed oil. The process of my invention may be readily understood by reference to the attached drawings illustrating modifications of the same.

For purposes of description, it is assumed that the feed oil is passed through a bed of bauxite although it is to be understood that a continuous operation may be employed in which, if desired, a slurry of bauxite is utilized. Referring specifically to the figure, it is also assumed that the nitrogen base containing feed oil is a petroleum oil boiling in the kerosene boiling range. The feed oil is introduced into initial contacting zone 1 by means of feed line 3. It is to be understood that any number of zones may be utilized and may be arranged in any suitable manner. The feed oil flows upwardly through zone 1 and contacts a bed of bauxite which preferably comprises a small particle size so that a relatively large surface area is secured. Temperature and pressure conditions are adjusted in a manner so as to substantially completely remove the nitrogen bases comprising aryl and alkyl amines and complex derivatives of pyridine, quinoline, pyrrole, and pyrazole from the feed

oil. The feed oil is withdrawn from initial contacting zone 1 by means of line 4, withdrawn from the system, and handled in any manner desirable. At the end of a fixed time period in which the effectiveness of the bauxite decreases to a predetermined efficiency, the feed oil is passed into secondary bauxite contacting zone 2 by means of line 5, and withdrawn by means of line 6.

The spent bauxite in contacting zone 1 containing the adsorbed nitrogen bases is handled in a manner to remove and segregate these compounds and to regenerate the bauxite. This is preferably accomplished by washing the bauxite with suitable solvents. For the purposes of description it is assumed that the bauxite is initially contacted with a relatively low boiling petroleum oil solvent having a preferential solubility for petroleum feed oil constituents remaining in the bauxite bed. This petroleum oil washing solvent may be introduced into contacting zone 1 by means of line 7 and withdrawn by means of line 8. The bauxite bed is then contacted with a solvent having a preferential selectivity for the nitrogen base compounds, which for the purpose of description is taken to be water. The water is introduced into initial contacting zone 1 by means of line 9 and withdrawn by means of line 10. Sufficient water is introduced at a temperature and pressure which is adapted substantially fully to remove the nitrogen base compounds from the spent bauxite bed. The bauxite bed, free of petroleum feed oil and adsorbed nitrogen bases and related compounds, is then contacted and treated in a manner adapted to fully regenerate the same, after which it is contacted with additional fresh feed oil.

At the end of the cycle in which the efficiency of the bauxite in contacting zone 2 drops to a predetermined value, the fresh feed oil is again passed into the regenerated bauxite in zone 1. The bauxite in contacting zone 2 containing the adsorbed nitrogen bases is then handled in a manner similar to that described with respect to zone 1 in order to remove and segregate the nitrogen bases and to regenerate the bauxite. This is accomplished by initially washing the bauxite bed with a relatively low boiling petroleum oil solvent which is introduced by means of line 11 and withdrawn by means of line 12. The adsorbed nitrogen bases are removed by contacting the bauxite with a preferential solvent for the nitrogen base compounds which is introduced by means of line 13 and withdrawn by means

of line 14. This solvent preferably comprises water. The spent bauxite is then regenerated by suitable means, such as by burning, steaming with superheated steam or otherwise treated.

The aqueous solution of nitrogen bases which is removed from the respective contacting zones by means of line 10 and 14, respectively, is introduced into nitrogen base recovery zone 15 by means of line 16 in which the nitrogen bases are separated from the aqueous layer by suitable means. For purposes of illustration it is assumed that recovery zone 15 comprises a separation unit in which the nitrogen bases are removed overhead by means of line 17 and the water removed as a bottoms by means of line 18. The nitrogen bases may be further refined or handled in any desirable manner.

When the feed oil containing the nitrogen bases also contains petroleum oil phenols, these latter materials are likewise adsorbed on the bauxite and removed in the aqueous layer. Under these conditions the aqueous solutions removed from the respective contacting zones 1 and 2 by means of lines 10 and 14, respectively, are handled in a manner to segregate the nitrogen bases from the phenolic type compounds. This is preferably accomplished by introducing the aqueous solution into treating plant 19 by means of line 20, in which it is contacted with a dilute mineral acid solution such as a dilute sulfuric acid solution which is introduced by means of line 21. The upper layer comprising phenolic constituents is removed by means of line 27 while the lower layer comprising a dilute sulfuric acid solution extract containing the nitrogen bases is removed by means of line 22 and passed into neutralization unit 23. In neutralization unit 23 the acid layer is contacted with a neutralization agent, as for example caustic soda, which is introduced by means of line 24 under conditions to neutralize the acidic constituents. Under these conditions the nitrogen bases separate as an upper layer and are removed from neutralization unit 23 by means of line 25 while the aqueous layer is removed by means of line 26.

The process of the present invention may be widely varied. It is to be understood that either a batch operation or a continuous operation as for example, utilizing a bauxite slurry may be employed. The feed oil may be any mineral oil, but preferably comprises petroleum oils boiling in the range from about 300 to 600° F., preferably boiling in the range from about 300° F. to 550° F. In general the feed oils should preferably comprise oils which are free of naturally occurring acidic oxygen containing compounds as for example phenols and naphthenic acids and contain nitrogen bases comprising aryl and alkyl amines and complex derivatives of pyridine, quinoline, pyrrole, and pyrazole.

The bauxite preferably comprises a native aluminum hydroxide containing from 50% to 70% of Al₂O₃ and from 25% to 30% of water. In general it is preferred that the bauxite be activated by burning the same at a temperature above about 500° F. to 900° F., preferably at a temperature from about 600° F. to 800° F.

The operating conditions likewise may be widely modified. The flow of the respective treating agents may be either upflow or downflow. Temperatures and pressures may vary and will depend upon the particular feed oil being treated, the quantity and character of the nitrogen bases present, as well as upon the particular bauxite being used and upon the feed rates and particle

size. In general it is preferred to employ atmospheric temperatures and pressures, although temperatures in the range from about 30° F. to 250° F. may be employed in particular instances.

5 If the petroleum oil be of a relatively high viscosity, it may be desirable to employ heating means or to dilute the oil with an inert dilution solvent, as for example a relatively low boiling petroleum oil or with a relatively low boiling hydrocarbon constituent.

The feed rates may vary considerably depending upon the general operating conditions, the character of the feed oil being treated, as well as upon the type of bauxite being employed. When the process comprises the utilization of stages, feed rates are in the general range from one to seven volumes of oil per volume of bauxite per hour. The preferred rates are from two to four volumes of oil per volume of bauxite per hour. When employing a slurry, the amount of slurry is preferably in the range from one volume of bauxite per fifteen to twenty-five volumes of oil.

15 Although it is not essential, it is preferred that the bauxite after contact with the oil be washed with a solvent which will remove occluded oil portions from the bauxite prior to treating the bauxite to remove the adsorbed nitrogen bases. This solvent may be any relatively low boiling hydrocarbon. A desirable material comprises naphtha boiling in the range from about 200° F. to 300° F.

20 The nitrogen bases are preferably removed from the bauxite by treating with water at normal temperatures and pressures. The amount of water employed may vary widely depending upon the quantity of nitrogen bases present and the particular bauxite employed. In general it is preferred to employ from about one to four volumes of water per volume of bauxite in order to displace the nitrogen compounds. A preferred modification of utilizing water at normal temperatures and pressures for the displacement of the nitrogen compounds is to agitate the mass with air or a similar agitating means. Under certain conditions it may be desirable to employ heated water or steam in order to remove the nitrogen bases, although in general this method is not preferred. If steam be employed it is preferred that the steam operation be conducted at a temperature in the range from about 600° F. to 800° F. The aqueous solution, after removal from the bauxite bed, will form two phases comprising a nitrogen base phase and an aqueous phase. The nitrogen base phase is separated and may be further refined in any manner desirable. Although the aqueous phase may be distilled in order to remove any relatively low boiling soluble nitrogen compounds present, it is preferred to recirculate the same as a solvent directly to the bauxite contacting units.

25 When the feed oil also contains naturally occurring oxygen containing acidic compounds, as for example phenols and naphthenic acids, the aqueous solution removed from the bauxite is contacted with a mineral acid, as for example sulfuric acid. Preferred results are secured when the aqueous solution is contacted with a dilute sulfuric acid solution having a concentration in the range from 20 to 50%. This concentration of course will vary depending upon the type of nitrogen bases present, the type of naturally occurring oxygen containing acidic compounds present, as well as upon the concentration of the respective constituents. When using a sulfuric acid solution of this concentration it is

preferred that from one half to one volume of sulfuric acid be used per volume of aqueous solution.

The acid solution of nitrogen bases after separation of the phenolic constituents is neutralized in any suitable manner in order to segregate the nitrogen bases. However, in general the preferred neutralizing agents are alkali metal hydroxide solutions such as a sodium hydroxide solution.

In order further to illustrate the invention the following examples are given which should not be construed as limiting the same in any manner whatsoever.

Example 1

A feed oil comprising 100 milligrams of nitrogen bases per 100 milliliters of feed oil was percolated through bauxite having a specific gravity of about 0.8 and a mesh of about 30 to 60. Atmospheric temperature and pressure was employed. The feed rate used was one volume of feed oil per volume of bauxite per hour. A yield of 16 volumes of nitrogen base-free filtrate per volume of bauxite was obtained.

The quality of the treated oil as compared to the feed oil was improved as seen by the following:

	Color, Saybolt	Direct oxidation color*
Feed oil.....	+24	8 R
Treated oil.....	+27	+26 S

*Refer to van Senden, Proc. World Pet. Cong. II, 1933.

The bauxite was washed with a light petroleum oil solvent and the nitrogen bases then recovered from the bauxite by treatment with water.

Example 2

A feed oil comprising 100 mg. of pyridine per 100 ml. of oil was passed through burned Alabama bauxite at room temperature. The feed rate was one volume of oil per volume of bauxite per hour. A yield of fifteen volumes of pyridine free oil per volume of bauxite was secured. The bauxite was treated with a petroleum oil solvent and the nitrogen bases then removed by treatment with water.

What I claim as new and wish to protect by Letters Patent is:

1. Process for the segregation and recovery of nitrogen bases from oils comprising contacting a nitrogen base containing feed oil with bauxite under conditions to remove the nitrogen bases from the treated oil, separating the bauxite from the feed oil and removing the nitrogen bases therefrom by means of an aqueous solvent, removing the aqueous solvent and recovering the nitrogen bases.
- 5 2. Process in accordance with claim 1 in which said aqueous solvent is water, and in which the nitrogen bases are recovered from said solvent by distillation.
- 10 3. Process in accordance with claim 1 in which said feed oil is a petroleum oil which boils in the range from about 300° F. to about 600° F.
- 15 4. Process for the segregation and recovery of nitrogen bases from oils containing phenolic type constituents comprising contacting a feed oil containing nitrogen bases and phenolic type constituents with bauxite under conditions to remove the nitrogen bases from the feed oil, separating the treated feed oil and treating the bauxite with an aqueous solvent for the nitrogen bases, removing the aqueous solvent containing the nitrogen bases, treating the solvent with a weak mineral acid whereby the nitrogen bases separate from phenolic type constituents, separating the resulting acid layer, neutralizing the same and recovering the nitrogen bases therefrom.
- 20 5. Process in accordance with claim 4 in which said solvent is water.
- 25 6. Process in accordance with claim 4 in which said feed oil is a petroleum oil which boils in the range from about 300° to about 600° F.
- 30 7. Process for the segregation and recovery of nitrogen bases from mineral oils comprising contacting a nitrogen base containing feed oil with bauxite under conditions to remove the nitrogen bases from the treated feed oil, separating the bauxite and treating the same with water, removing the aqueous solution whereby a higher boiling nitrogen base phase separates as a separate phase, separating said nitrogen base phase from the aqueous phase, distilling said aqueous phase to segregate relatively low boiling nitrogen bases therefrom.
